UNITED STATES PATENT OFFICE.

LOUIS E. LADD, OF PROVIDENCE, RHODE ISLAND, ASSIGNOR TO POTTER AND BUFFINTON COMPANY, A CORPORATION OF RHODE ISLAND.

DESIGN FOR A JEWELRY-GALLERY.

47,400.

Specification for Design.

Patented June 1, 1915.

Application filed January 25, 1915. Serial No. 4,381. Term of patent 7 years.

To all whom it may concern:

Be it known that I, LOUIS E. LADD, a citizen of the United States, residing at Providence, in the county of Providence and State of Rhode Island, have invented a certain new, original, and ornamental Design for Jewelry-Galleries, of which the following is a specification.

A jewelry gallery is an article of manufacture consisting of a series of uniform ornaments formed in a continuous length and adapted to be affixed to an article of jewelry for ornamental purposes.

In the accompanying drawings which form a part of this specification, Figures 1, 2, and 3 are top plan, side, and bottom plan views respectively of a gallery embodying my new design.

I claim:

The ornamental design for a jewelry gallery, as shown.
